10 Claims. (Cl. 49—253)

ABSTRACT OF THE DISCLOSURE

A closure, such as a casement window, has a movable sash pivotally supported by outwardly swinging arms from a stationary frame. The arms permit limited swing-out of the sash to present the weather side of the sash to the frame while precluding abutment of the swung out sash with the wall in which the frame is fixed. A stationary flange is provided on the frame, behind which a marginal edge of the sash pivots and slides to obtain a weathertight seal.

This invention relates to closures and especially to window casements wherein the sash may be swung out from its frame and rotated so as to permit manual access to the normal outer or weather face of the sash from within the building.

Window casements are customarily of either of two types. Of the first type are those wherein the sash is pivotally mounted on a vertical axis within the frame. When rotated, half of the window swings into the building. The weather-proofing seals are customarily of the wiping type. Such windows preclude the normal usage of the area within the building within the radius of the window, and suffer from rapid deterioration of the weather-proofing seals, particularly at the corners where the seals have to flex in two directions. Of the second type are those wherein the sash is pivotally mounted on a vertical axis from arms, which arms are pivotally mounted on a vertical axis within the frame. When rotated, the window swings either into or away from the building on its arms, and may be rotated within its arms. If the window swings inwardly, it precludes the normal usage of the area within the radius of the window. If it swings outwardly, it is subject to the effects of the wind in the same manner as a sail. If the window is large, such as in modern, non-residential buildings, the force on the window provided by even a light wind may be manually unmanageable. Any lack of parallelism between the supporting arms, may cause a springing of the sash. The weather-proofing seals may be made of the compression type. A window of this type was early taught in U.S. Patent No. 652,216, issued June 19, 1900.

Accordingly, it is an object of this invention to provide a casement window, having a sash pivotally supported by outwardly swinging arms, to provide access to the weather face of the sash from the interior of the building, with excellent weather-proofing, wind control, non-springing and esthetic characteristics.

A feature of this invention is the provision of a casement window having a sash pivotally supported on a vertical axis in an integral arm support, which support is pivotally mounted for limited rotation to provide access from the interior of the building to the weather side of the sash, most of the integral arm support being concealed from view, with means for fully compressing the weather-proofing seals around the sash when the window is closed.

These and other objects, features and advantages of this invention will be apparent from the following specification taken in conjunction with the accompanying drawings in which:

2

FIG. 1 is a perspective view of an embodiment of this invention, the window being shown closed and viewed from the interior of the building;

5 FIG. 2 is a perspective view of the embodiment of FIG. 1, the window being shown in its maximum swung open disposition and viewed from the interior of the building;

FIG. 3 is a perspective view of the embodiment of FIG. 2, viewed from the exterior of the building;

10 FIG. 4 is a plan view in cross-section of the embodiment of FIG. 3, taken along the plane 4—4 of FIG. 5;

FIG. 5 is an elevational view in cross-section taken along the plane 5—5 of FIG. 4;

15 FIG. 6 is an elevational view in cross-section taken along the plane 6—6 of FIG. 4;

FIG. 7 is a detail of a view similar to FIG. 3, with the sash rotated to less than its maximum swing, viewed from the outside; and

20 FIG. 8 is a detail of a view similar to FIG. 2, with the sash rotated to its maximum swing, viewed from the inside.

The embodiment of the invention herein illustrated comprises a window casement having a frame 10 which is fixed within the building wall 12, an integral arm support 14 which is pivotally mounted to the frame, and a sash 16 which is pivotally mounted to the support.

30 The frame 10 may be bent out of sheet metal to provide a stepped cross-section having a lock or hinge remote jamb 18, with a weather lateral face 20, a cross face 22, a lateral face 24, a cross face 26, a seal lateral face 28, a cross face 30 and an interior lateral face 32. The frame also has a hinge jamb 34, a header 36 and a sill 38. The hinge jamb has a weather lateral face 40, a cross face 42, a seal lateral face 44, a cross face 46; 35 and an interior lateral face 48. The header and the sill are similar and each has a weather lateral face 50, a cross face 52, a seal face 54, a cross face 56, and an interior lateral face 58.

40 The sash 16 may be bent out of sheet metal to provide four sides each having a central beam 60, a U channel 62 for receiving a pane of glass 64, and a C channel 66 for receiving a length of resilient sealing material 68.

45 The integral arm support 14 comprises a vertical shaft 70 having an upper and a lower portion 72, which may be of reduced diameter. An upper and a lower arm 74 each have a bore 76 therethrough, adjacent one end, through which bore a respective portion 72 is disposed and secured, as by welding. An upper and a lower bearing block 78 are respectively secured, as by screws 80, to the cross faces 52 of the header and the sill adjacent the hinge jamb. Each block 78 has a bore 80 therethrough, through which bore a respective portion 72 is disposed with freedom to rotate. A thrust washer 82 is 50 respectively disposed over the projection 72 between the confronting surfaces of the arm and the block. The block 78 may be cut out at 84 to receive a projecting lip 86 which conceals most of the block 78 when the window is closed. Each arm 74 has a stepped bore 88 adjacent the other end, through which bore is fixed a respective stepped pivot 90. The reduced end 92 of the pivot 90 passes through a thrust washer 94 into a bore 96 in the beam 60 of the sash. The two pivots 90, the two arms 74 and the shaft 70 are integral. The central axes of the 55 two pivots 90 are coaxial and parallel to the central axis of the shaft 70.

60 A U shaped cover 98 is secured, over the shaft 70, to the seal face 44, by suitable means, such as rivets 100. A shield 102, which may be L shaped, having a lateral leg 104, is secured to the cross face 42, by suitable means, such as screws 106. The ends of the leg

104 are cut out at 103 to clear the arm 74 for rotation and to provide a surface 110 to abut the weather face of the arm 74 and to limit its maximum rotation with respect to the window frame.

A skirt 112 is respectively fixed to the upper and lower surfaces of the sash, by any suitable means, up to the ends of the arms 74 to shield the gap between the sash and the surface 52 where the block 78 is absent, and to provide a respective surface 114 to abut the weather face of the respective arm 74 to thereby limit the maximum rotation of the sash with respect to the support arms. 5

It will be appreciated that by permitting the sash to rotate with respect to the arms as the arms are rotating with respect to the frame, the hinge edge of the sash may be brought quite close to the edge of the shield leg 104. 15 In fact, the shield is here shown as made to overlap the weather face of the sash, and will act as a fulcrum for the sash to compress the weather stripping tightly when the edge of the sash is initially tucked between the shield leg 104 and the seal face 44, and the sash is subsequently fully closed. 20

In an exemplary window casement, the following dimensions, which are not to be taken as limitative, are used. The overall width of the sash, from outer edge to outer edge is 2'4". The radius of the arm 74 between 25 the central axes of the shaft 70 and the pivots 90 is 10". The distance between the central axis of the shaft 70 and the weather face of the shield leg 104 is 7/8". The height of the sash is 7'8".

A latch or lock 116 is provided between the lock jamb 30 18 and the adjacent hinge remote side of the sash. The latch has a lever with a cam on the sash and a cam follower on the jamb to permit a tight closing of the sash and compression of the weather seals 68.

The stop edge 110 is suitably spaced with respect to 35 the arms 74 so as to preclude a shifting of the hinge remote edge of the sash beyond comfortable manual reach when the window is opened and the weather face of the sash is swung inwardly. The stop edge 114 is suitably spaced with respect to the arm 70 so as to preclude the abutment of the hinge remote edge of the sash with the weather face of the building. When the window is opened and the weather face of the sash is swung inwardly, the pivot 90 is made as close to one half 40 the width of the sash as is consistent with convenient manual reaching of the weather face of the sash when it is rotated. It is desirable to locate the pivot relatively close to the middle of the width of the pivot so as to approach a balance of the areas of the sash about its pivot, and thus to minimize any tendency of the wind to swing the sash about its pivots. The stops 110 and 114 serve the additional function of limiting the sash when 45 it is opened to a maximum position which is substantially parallel to the weather face of the building. Thus, should a wind blowing parallel to the weather face of the building blow the sash and the supporting arm structure about the shaft 70, its effect will be minimized at maximum swing since the wind will be blowing at the sash edge on.

It will be appreciated that when the window is closed 50 the sash compresses the weather stripping uniformly against the seal faces of the frame, ensuring a weather tight seal. During opening and closing of the sash there is no uneven wear of the weather stripping. The shield leg 104 protects the shaft recess from the accumulation 55 of foreign matter such as dirt or snow.

While I have shown and described the preferred embodiment of the invention, it will be understood that the invention may be embodied otherwise than as herein specifically illustrated or described, and that certain changes in the form and arrangement of parts and in the specific manner of practicing the invention may be made without departing from the underlying idea or principles 60 of this invention within the scope of the appended claims. 65

What is claimed is:

1. A closure for a wall comprising:

a movable sash;

movable support means pivotally coupled to said frame and pivotally coupled to said sash for normally holding said sash within and against said frame and for permitting rotation of said sash with respect to said support means concurrently with permitting rotation of said support means with respect to said frame, whereby said sash may be swung out of said frame and rotated to present its weather face towards said frame;

first stop means having one portion fixedly disposed on said fixed frame and having the remaining portion for engagement with said one portion fixedly disposed on said support means for limiting the maximum angle of rotation of said support means with respect to said frame; and

second stop means having one portion fixedly disposed on said sash and having the remaining portion for engagement with said one portion fixedly disposed on said support means for limiting the maximum angle of rotation of said sash with respect to support means;

whereby said first and second stop means limit the maximum swing of said sash from said frame to preclude abutment of said sash with the wall.

2. A closure according to claim 1 wherein said first and second stop means limit the maximum swing of said sash to a position substantially parallel to said wall.

3. A closure according to claim 1 wherein said one portion of said first stop means includes a first surface on said frame,

said remaining portion of said first stop means includes a second surface on said movable support means, whereby on said support means rotating through said maximum angle of rotation with respect to said frame, said first and second surfaces mutually abut to halt rotation through an angle greater than said maximum angle; and

said one portion of said second stop means includes a third surface in said sash,

said remaining portion of said second stop means includes a fourth surface on said movable support means,

whereby on said sash rotating through said maximum angle of rotation with respect to said support means, said third and fourth surfaces mutually abut to halt rotation through an angle greater than said maximum angle.

4. A closure according to claim 1 wherein said frame has a lateral seal face which is overlapped by said sash,

a resilient weather seal being disposed between the confronting faces of said frame and said sash along the overlap thereof.

5. A claim for a wall comprising:

a frame fixed in the wall;

a movable sash;

movable support means pivotally coupled to said frame and to said sash for normally holding said sash within and against said frame and for permitting rotation of said sash with respect to said support means concurrently with permitting rotation of said support means with respect to said frame, whereby said sash may be swung out of said frame and rotated to present its weather face towards said frame;

first stop means disposed on said frame and support means for limiting the maximum rotation of said support means with respect to said frame;

second stop means disposed on said support means and said sash for limiting the maximum rotation of said sash with respect to said support means, thereby to preclude abutment of said sash with the wall;

said frame having a lateral seal face which is overlapped by said sash;
a resilient weather seal being disposed between the confronting faces of said frame and said sash along the overlap thereof;
said frame having a header and a sill,
said support means comprising a vertical shaft pivotally mounted at its ends to the header and the sill respectively of the frame, and having two arms, each arm being respectively fixed at one end thereof to said shaft and having a pivot for rotatably supporting said sash at the other end thereof, the central axes of said pivots being coaxial and parallel to the central axis of said shaft;
said frame having a hinge jamb adjacent to said shaft and a lock jamb remote from said shaft, and a projection means spaced from the lateral seal face of said hinge jamb, one marginal portion of said sash, when said closure is open and being closed, being adapted to be disposed between said projection means and said lateral seal face of said hinge jamb and to be pivoted against said projection means as another marginal portion of said sash is moved against said lateral seal face of said lock jamb to close and seal said sash against said frame. 25

6. A closure according to claim 5 wherein said shaft is mounted in bearing blocks to said header and sill of said frame and said projection means projects over said shaft. 30

7. A closure according to claim 6 wherein said projection means is elongated and in combination with said hinge jamb and said sash when closed provides an enclosure around said shaft. 30

8. A closure according to claim 1 wherein
said frame includes a header and a sill, and
said support means comprises a vertical shaft pivotally mounted at its ends to the header and the sill respectively of the frame and having two arms, each arm being respectively fixed at one end thereof to said shaft and having a pivot for rotatably supporting 40 said sash at the other end thereof, the central axes of the pivots being coaxial and parallel to the central axis of said shaft; and
said frame further includes a hinge jamb adjacent said

5

shaft and a lock jamb remote from said shaft, and the lateral distance between the edge of said sash adjacent the hinge jamb to said central axis of said pivots is less than the lateral distance between the edge of said sash adjacent the lock jamb to said central axis of said pivots.

9. A closure according to claim 3 wherein
said frame includes a header, a sill, a hinge jamb and a lock jamb;
and said support means comprises a vertical shaft pivotally mounted at its ends to said header and sill respectively, of said frame adjacent said hinge jamb, and having two arms, each arm being respectively fixed at one end thereof to said shaft and having a pivot for rotatably supporting said sash at the other end thereof, the central axes of said pivots being coaxial and parallel to the central axis of said shaft;
said first surface on said frame being formed on a first projection extending from at least one of said header and sill between said hinge jamb and the adjacent arm and forwardly of said shaft towards the weather side of the wall, and said second surface is formed on said adjacent arm; and
said third surface on said shaft being formed on a second projection extending from said sash and disposed on one side of such adjacent arm when said sash is closed with the weather side out, and adapted to swing around said adjacent arm and its pivot to the other side of said adjacent arm when said sash is opened with the weather side in. 25

10. A closure according to claim 9 wherein
said first projection is a notch cut into a shield extending along said hinge jamb between said header and said sill; and
said second projection is a skirt extending from said sash. 30
